UNITED STATES PATENT OFFICE.

JOHN E. FISHER, OF GRAND RAPIDS, MICHIGAN, ASSIGNOR OF ONE-HALF TO CLAUD M. HURD, OF GRAND RAPIDS, MICHIGAN.

TOY BUILDING BLOCK.

Application filed April 4, 1921. Serial No. 458,312.

To all whom it may concern:

Be it known that I, JOHN E. FISHER, a citizen of the United States, residing at Grand Rapids, in the county of Kent and State of Michigan, have invented new and useful Improvements in Toy Building Blocks, of which the following is a specification.

The present invention relates to toy building blocks; and its object is to provide devices of that character which may be readily and securely assembled to form toy houses and the like of various shapes and sizes, and which may be as readily disassembled.

This object is attained by, and the invention finds preferable embodiment in, the blocks or members which, together with illustrative examples of their assembling, are hereinafter particularly described and illustrated by the accompanying drawings, in which:—

Figure 1 is an outside view in perspective of a portion of a toy house formed by assembling my building blocks;

Figure 2 is an inside view of the same;

Figure 3 is a view of the roof portion of the toy house, the roof members or plates being shown in vertical section;

Figure 4 is a view of a door for the toy house and the door's mounting;

Figure 5 is a top plan view of meeting rafter members of a toy house or tower;

Figure 6 is a side view thereof;

Figure 7 is an upper end view of such a rafter member;

Figure 8 is a side view of the same;

Figure 9 is a view in perspective of forms of beam members partially assembled;

Figure 10 is a side view of one of the beam members seen in Figure 9 and a cross sectional view of the other two beam members taken on a vertical plane corresponding to line 10—10 of Figure 9, the three beam members being completely assembled in this view;

Figure 11 is a top plan view of one of said beam members;

Figure 12 is a view of another form of the beam members, two of which form of members are shown in that relative position in which they are about to be moved together to assemble them;

Figure 13 is a view of one of the beam members seen in Figure 12 but turned to another position;

Figure 14 is a side view of another form of beam member together with end views of such members as are shown in Figures 12 and 13 (sectioned on lines 14—14 of said figures) in position about to be assembled; 60

Figure 15 is a view in perspective of a post member or block, the middle portion being broken away;

Figure 16 is a view in perspective of a filler member or block; 65

Figure 17 is an edgewise view of the same;

Figure 18 is a view in perspective of a plate member or block;

Figure 19 is an end view of the same;

Figure 20 is a sectional view of a part 70 thereof taken on a horizontal plane corresponding to line 20—20 of Figure 19; and

Figure 21 is a plan view showing one of the post members and two plate members connected thereto, the post member being 75 shown in horizontal section.

In the embodiments of the invention chosen for illustration by the drawings and for detailed description in the body of this specification, the post members or blocks 1 have 80 vertically extending sockets 2 in their ends and have means, preferably the grooves 3 extending in the longitudinal direction of the posts, for detachably connecting the ends of the plate members or blocks 4 to the sides 85 of the posts. These plates may be provided with tongues 5 at their ends of less thickness than the body of the plates which tongues are inserted into the grooves of a pair of posts between which the plates are positioned and thus held. The posts are desirably of a length registering with the vertical width of a plurality (two in the construction illustrated) of the plates. These plates are usually of the rectangular form seen in Figure 18, but modifications thereof may be employed, as the triangular plates 6 for the gable ends of a toy house as seen in Figures 1, 2, and 3. Some of the plates may have notches 7 in their lower or upper edges 100 whereby windows may be provided, as seen in Figures 1 and 2.

The posts are connected at their tops or bottoms (or both) by horizontally disposed beam members or blocks having orifices 9 105 in their end portions, through which pins 10 may be removably thrust into the sockets 2 of the posts to bind the beams, posts and plates securely in assembled position; and posts placed end to end are connected by such 110

a pin thrust into the sockets of their abutting ends. These beams may be of various forms whereby different combinations of the assembled blocks may be made. A usual form 11 of such beams is particularly shown in Figures 12 and 13. In this form the beam has shoulders 12, 13 adjacent its ends, respectively and end portions extending beyond said shoulders, one end portion 14 thus extending from an upper part, as the upper third, of the cross section of the body portion of the beam (as seen in Figure 13) the other end portion 15 extending from a lower part, as the third next below said upper part or third, said end portions having the vertically extending orifices 9 therethrough. The same form of beam but turned half way around on its longitudinal axis is seen in Figure 12. The other part or third of the cross section of the body of the beam 11 may be filled by a square filler member or block 16 seen in Figures 16 and 17 having a pin-receiving orifice 17 therethrough.

It will be seen that the abutting of the square end portions of adjacent beams, whether aligned or at right angles to each other in the assembled and pinned-together position of the beams, prevents them from turning on the pin's axis relatively to each other.

Another form of beam 18 is seen in Figure 14 having the end portions 19 extending from the same—the lower—third of the cross section of the beam's body portion; and another form of beam 20 is seen in Figures 9, 10 and 11, which beam is of double length and has at its middle a transverse recess 21 thereacross extending for a distance of two thirds of the vertical thickness of the beam, with a vertically extending orifice 22 through the bottom of the recess. Beams of form 11 shown in Figures 12 and 13 may be combined with this beam 20 in the manner indicated in Figures 9 and 10 to form the meeting corners of four rooms in the toy house.

A rafter member 25 having grooves 31 in its opposite sides receiving the plates 41 may be employed to form the roof of the toy house. Such a rafter inclined in a vertical plane has a vertically extending orifice 26 receiving a pin 101 carried in the socket in the upper end of a post, and is thereby secured in place. The upper end of the rafter may have its opposite sides 27, 28 inclined toward each other and lying in vertical planes meeting at the central longitudinal plane of the rafter, as particularly shown in Figures 5, 6, 7 and 8, whereby a tower having four sloping roof portions meeting at the tower's center may be formed. A door 30 may be provided between posts and having sockets 31 in its upper and lower edges turnably receiving pins 33 whose other ends are held in sockets 34 in upper and lower

beams, as seen in Figure 4. It is manifest that many combinations of the blocks or members may be made, examples being shown in Figures 1, 2 and 3.

The invention being intended to be pointed out in the claims, is not to be limited to or by details of construction of the particular embodiment or embodiments thereof illustrated by the drawings or hereinbefore described. 75

I claim:

1. In devices of the character described; a post having a socket in its end; beams, each having shoulders adjacent its ends respectively and end portions extending beyond said shoulders, one end portion thus extending from the upper third of the cross section of the body portion of the beam and the other end portion extending from that third of the cross section of said body portion which is next below said upper third, said end portions having vertically extending orifices therethrough; a pin adapted to be removably thrust through said orifices and into said socket; plates adapted to be detachably connected at their ends to the sides of the post. 80

2. In devices of the character described; a post having a socket in its end; a beam having a transverse recess extending two-thirds of the vertical thickness of said beam and having a vertically extending orifice through the bottom of the recess; a pair of beams each having a shoulder adjacent an end thereof and an end portion extending beyond said shoulder, the end portion of one beam of said pair extending from the upper third of the cross section of its beam and the end portion of the other beam of said pair extending from that third of the cross section of its beam which is next below the upper third thereof, said end portions of said pair of beams having vertically extending orifices therethrough; a pin adapted to be thrust through all said orifices and into 100 said socket. 105

3. In devices of the character described; plates; rafters inclined in vertical planes and having grooves in their opposite sides extending in their longitudinal direction 110 adapted to removably receive and hold the ends of the plates, the upper end of each of the rafters having oppositely disposed sides inclined toward each other and lying in vertical planes meeting in the middle 115 longitudinal vertical plane of the rafters respectively. 120

4. In devices of the character described; a post having a socket in its end; a beam having a transverse recess extending for a portion of the vertical thickness of said beam and having a vertically extending orifice through the bottom of the recess; a pair of beams each having a shoulder adjacent an end thereof and an end portion extend- 125 130

ing beyond said shoulder, said end portions having vertically extending orifices therethrough and being offset from each other and from that portion of the first 5 mentioned beam which is below its recess; a pin adapted to be thrust through all said orifices and into said socket.

5. In devices of the character described; plates; three or more rafters inclined in vertical planes and having grooves in their 10 opposite sides extending in their longitu-

dinal direction adapted to removably receive and hold the ends of the plates, the upper end of each of the rafters having oppositely disposed sides inclined toward each other 15 and lying in vertical planes, whereby the rafters' upper ends are adapted to meet and form a peak.

In testimony whereof I have hereunto set my hand at Grand Rapids, Michigan, this 20 2nd day of April, 1921.

JOHN E. FISHER.
